L. L. TREMAN.
Gas Meter.

No. 233,645.

Patented Oct. 26, 1880.

UNITED STATES PATENT OFFICE.

LAFAYETTE L. TREMAN, OF ITHACA, NEW YORK.

GAS-METER.

SPECIFICATION forming part of Letters Patent No. 233,645, dated October 26, 1880.

Application filed April 23, 1880. (No model.)

To all whom it may concern:

Be it known that I, LAFAYETTE L. TREMAN, of Ithaca, Tompkins county, New York, have invented an Improved Gas-Meter, whereof the 5 following is a specification.

My meter has an outer case, which contains a fluid, in which revolves the ordinary measuring-drum, which I pivot to the frame, partially inclosing it, and which frame and drum I float 10 by means of one or more air-chambers attached to or making a part of the frame, for the purpose of maintaining a constant level of the fluid in the measuring-drum, be the height or quantity of fluid in the outer case what it may, 15 a level that cannot be always the same in a meter as usually constructed. The means by which I accomplish this will be apparent as I describe my invention.

Figure 1 is a side elevation of my meter, looking on the front of the meter and drum, the front wall of the case being removed, with a portion of the entrance-pipe and a portion of the gas-seal or the outer tube of the variable register shaft. Fig. 2 is the left-hand end elevation of 25 my meter, the left-hand end wall being removed, and the shaft-seal being in section, and a part of the left-hand division of the upper part of the air-float being cut away to show the screw-thread on the drum-shaft, the lower 30 register cog-wheel, and the cup-cavity for the shaft-seal more perfectly.

All parts of my invention are perfectly clear and to be understood by Fig. 2 alone, were there no other figures; but to make perfect 35 clearness and perspicuity more clear I add the remaining figures, in which—

Fig. 3 is a view of that very common art, a sliding stud between two ways; Fig. 4, an enlarged view of the measuring-drum, with gas- 40 entrance pipe in the gas-space, between the usual curved front wall and the usual partition-wall of the drum. The gas-pipe is shown fast to the front of the outer case, which it perforates. Fig. 5 is a view of the upper part of the 45 entrance-pipe fast to the frame B, and rising and falling with the frame and drum, and the lower part to the outer case, and a piece of flexible or rubber pipe connects the two ends of the entrance-pipe, which is another adapta-

tion of the entrance-pipe to the main object I 50 have in view, and it is apparent how it acts. Fig. 6 shows the very common art of making a slip-jointed shaft, as is also perfectly clearly seen in Figs. 1 and 2. The cup-cavity beneath the cog s and the air-chamber to float the drum, 55 made of the parts c c' c'', and the projections r r', to stop the drum if the fluid gets too high, and the projections m and n, to stop the drum if too low, are all clearly seen in Figs. 1 and 2.

In the figures, A A A is the outer gas and 60 fluid tight case, having the slide or guide ways fast to the inside of it, one on each end of the case near its top, and one on each of the ends near the bottom, making four such slideways, and they are inclined because the gas-entrance 65 pipe must enter the central aperture of the drum obliquely, and their angle of inclination suits the angle of the entrance-pipe; and B B' is the frame to which the measuring-drum is journaled, as seen in Figs. 1 and 2. This frame 70 is made of the air-chamber c beneath the drum, and has the two divided portions c' on the right hand of the shaft of the drum, the entrance-pipe and registering-shaft and lower 75 cog and the other portion, c'', on the left hand of these just-named parts. The shape of c' and c'' is shown to be rectangular and perpendicularly arranged until near their tops, when they flare outward, as shown in Fig. 2, somewhat like a boat-side, to insure the ready buoyancy and adjustment of the water-level in the 80 drum.

C is the drum that measures the gas, and it has the central aperture, d'', through which the gas-entrance pipe goes, which aperture 85 is no way different from that long in public use, except, perhaps, it is made a little larger in diameter. In the drum is the usual gas-space between the convex cap or head d and the section-wall d'. These parts are also old 90 structures long in public use. The measuring-sections are not represented, nor the arrangements of the longitudinal gas-entrance slits that let the gas into the sections, because they are old, well understood, and are unchanged 95 by my use of them. The usual screw-thread is on the shaft of the drum in the usual place, and it plays in the usual cog, s, in the usual

manner. By the side—preferably the left-hand side, as seen in Fig. 1—the gas-entrance pipe goes into the aperture d'' , and it is for this pipe, as well as the registering devices there, that the upper part of the air-chamber c is divided into c' and c'' .

The entrance-pipe is made of the outer part, F , the horizontal part f' , that pierces the case, and the inclined part f'' , all clearly seen in Figs. 2 and 4; and it will be apparent that if I float the drum the entrance-pipe can utilize only the space between the water-level D of the drum, near the aperture d'' and the top of the drum, and to do this in this space of several inches the part f'' of the entrance-pipe must be inclined, which, as I have said, 15 compels the ways $a a' a'' a'''$ to be inclined, in which the studs $b b' b'' b'''$ move. At the base of the entrance-pipe is the drip-chamber F' .

By the figures it is clear that the air-chamber c is made of the large chamber e beneath the drum, the shape of which is plainly shown, and of the two divisions c' and c'' , which give 25 an excess of air, to produce motion at all times beyond the friction and other contingencies of the drum, its frame, lower registering screw-thread and cog, and the slide-joint of the registering-shaft i . It is apparent that 30 this shape of the air-chamber is not absolutely essential—as, for example, round floats might be on the sides of the frame and not beneath the drum, or angular (base upward) floats, or other shapes, yet all attached directly to the frame, and with an excess of 35 floating power sufficient to fix the level line D of the drum accurately.

By the exit E the upper fluid-level is fixed, and by the inlet V the fluid is poured in the 40 meter.

The line D is the fluid-level of the drum, and varies, in respect to the meter-case, with the quantity of fluid in the meter. The fluid inlet and exit sets the line D to coincide with 45 the line E .

If the line D rises much above the line E , the stop r' , fast to the drum, strikes the stop r , fast to the case, and the drum stops, and no gas can be used. If the line D falls with the 50 frame and drum that control it too far below the line E , the projection or stop m strikes the projection or stop n , and that stops the drum, and no gas can be used. It is also apparent that the use of a flexible or rubber tube, spoken of above between the parts of the entrance-pipe relieves the meter of the 55 inclined ways and allows them to be perpendicular.

If the drum floats at variable levels, then it 60 is a matter of necessity that the shaft i , connecting the lower cog, s , with the screw-thread on the top of the shaft, be variable, as well as that the shaft be surrounded by a gas-seal. For this purpose I divide this shaft, leaving the

lower part with the cog-wheels on it, and the upper part with the screw-thread x on it, and that it may revolve, and yet be variable in length, I put about this divided shaft the tube or sleeve i' , fast to the upper part of the shaft and loose about the lower part of the shaft; 65 and in the lower part I put a stud, i'' , playing in a slot in the sleeve—a very common mechanical expedient, that needs no further explanation. The reason of this variable length of the shaft i is, that the drum may 70 float at varied levels and the register on the top of the meter be stationary; and i''' is the gas seal or pipe that incloses the divided and sleeved shaft i . Its top is fast to the case A , and its base is beneath the line D at all times, 75 and it is merely not to let the gas leak out of the meter. To give it this length the seal or tube i''' must go lower than the cog-wheel s , as that wheel is usually placed, and also through that wheel. Hence I make a cup-shaped cavity, s' , beneath that wheel, as is shown.

Except the wheel for feet, no part of the register is shown.

The part B' of the frame extends above the 90 air-chamber, as seen in Figs. 1 and 2, to give support to the studs $b b'$, as well as brace the frame.

The drip-collector F' is outside the meter. The pipe F opens into it.

Other parts familiar to those who make meters or understand them need no remark, as I have explained all changes I have made in the construction of my meter. Advantages and uses are apparent to those familiar with 100 the art to which it appertains.

I do not claim to be the first who made a floating measuring-drum, nor the first who made an adjustable device between the measuring-drum and register-cogs; but

What I claim is—

1. A measuring-drum, C , fixed by its journals to a floating frame, B , which drum and frame are floated by the air chamber or chambers c , fast to the frame, combined and arranged substantially as set forth.

2. The floating frame B , having studs b projecting from it into the guideways a , fast to the outer case, A , in which the studs move, in combination with the air-chamber c , and which frame and its drum C are thus guided in their rise and fall, as set forth.

3. The variable joint between the two divided ends of the gas-registering shaft i , one having the sleeve i' fast to it, and the other 120 the stud i'' fast to it, which stud plays in the slot in the sleeve, and thus makes adjustment of the variable distances between the cog-wheel fast to the frame B and the meter registering-cogs, as set forth.

4. A gas-meter constructed of an outer gas and fluid tight case, A , frame B , floated by the air chamber or chambers c , fast to or part

of the frame, the air-chambers *e*, drum *C*, inlet-pipe *F*, and jointed shaft *i*, combined and operating as set forth.

5. The arm or stop *m* on the end of the drum-shaft, and operating, in connection with the stop *n*, for stopping the drum when the fluid gets too low in the meter, as set forth.

6. The stud *r*, fast to the case *A*, and the stop *r'*, fast to the drum *C*, for stopping the drum when the fluid is too high in the meter, as set forth.

7. The cup-shaped cavity beneath the cog-wheel *s*, for aiding the gas-seal *i'''* when the fluid is high in the meter, as set forth.

8. The drip-collecting outside receptacle, *F'*, 15 at the base of the gas-entrance tube *F*, for receiving the fluids and overflow of the tube, as set forth.

LAFAYETTE L. TREMAN.
